Des. 224,036
Patented June 27, 1972

224,036

FINDING FOR A BROOCH OR THE LIKE

Maurice C. Faldborg, 29869 Marine View Drive,
Federal Way, Wash. 98002

Filed Aug. 5, 1970, Ser. No. 24,588

Term of patent 14 years

Int. Cl. D11—01
U.S. Cl. D45—19

Fig. 1.

Fig. 2.

Fig. 3.

FIG. 1 is a perspective view of a finding for a brooch or the like, showing my new design;

FIG. 2 is a front elevational view; and

FIG. 3 is a top plan view.

I claim:

The ornamental design for a finding for a brooch or the like, substantially as shown.
